UNITED STATES PATENT OFFICE.

CHARLES W. HUBBARD, OF WESTON, MASSACHUSETTS.

WINDING APPARATUS.

Application filed October 4, 1919, Serial No. 328,383. Renewed May 8, 1926.

This invention relates to winding apparatus of that general type shown in my prior Patents No. 1,232,686, July 10, 1917, and No. 1,258,411, March 5, 1918, and which 5 comprise a yarn receiver and a winding head which are rotatable relative to each other and which are arranged so that the winding head lays the yarn in layers extending transversely to the axis of rotation, 10 each layer comprising a plurality of loops.

The object of the present invention is to provide a novel winding mechanism of this type having improved means for actuating and controlling the laying arm and compensating arm, an improved means for feeding the yarn to the winding head and other features of improvement, all as will be more fully hereinafter set forth.

In order to give an understanding of my 20 invention, I have illustrated in the drawings some selected embodiments thereof which will now be described, after which the novel features will be pointed out in the appended claims.

25 In the drawings, Fig. 1 is a vertical sectional view of a winding apparatus embodying my invention;

Fig. 2 is a section on the line 2—2, Fig. 1;

Fig. 3 is a section on the line 3—3, Fig. 1;

30 Fig. 4 is a detail of the differential gear controlling the cams;

Fig. 5 is a plan view of the device;

Fig. 6 is a side elevation of the device showing the winding head separated from 35 the yarn receiver and indicating the manner in which the yarn is cut;

Fig. 7 is a section taken on the line 7—7, Fig. 6.

In the drawings, 1 indicates the yarn receiver which is preferably in the form of a cylindrical receptacle, 2 indicates a yarn support situated within the yarn receiver 1 and on which the yarn mass 3 is supported, and 4 indicates generally the winding head 45 by which the yarn mass 3 is built up in the yarn receiver in layers extending transversely to the axis of rotation.

The yarn support 2 may have any suitable construction, that herein shown being 50 similar to the yarn support which is illustrated and described in my Patent No. 1,394,732, dated October 25th, 1921.

55 The winding head 4 is fast on a shaft 5 journaled in suitable bearings 6, said shaft being rotated by some suitable means. For this purpose, I have shown a gear 27 fast

on the shaft 5 which meshes with and is driven by a driving gear 38 mounted on a shaft 39 journaled in the frame 40. Said winding head comprises a supporting member or housing 7 in which is received the differential gearing and cams to be hereinafter referred to and which supports a winding plate 8 that rests on the yarn mass 3. This winding plate 8 is sustained from 60 the housing or member 7 by means of two oppositely-disposed arms 9 and it is provided with a yarn-guiding slot 10 through which the yarn is delivered to the yarn mass, 65 all as usual in devices of this character. 70

One feature of my present invention relates to means for guiding and controlling the yarn as it is delivered through the guiding slot 10. Supported in the member 7 is a vertical rock shaft 11 which carries at its lower end a yarn-laying arm 12 and means are provided for oscillating the rock shaft 11 to cause the end 13 of said arm 12 to vibrate longitudinally of the slot 10. The yarn 14 is delivered to the yarn-laying arm 12 through the shaft 5 which is hollow for this purpose, and the vibration of the arm 12 will traverse the yarn back and forth in the slot 10, thus causing the 75 yarn to be laid in loops as in the above-mentioned patents. For thus vibrating the rock shaft 11 I employ herein a novel cam mechanism which is actuated by differential gearing situated within the housing 7. The upper end of the rock shaft 11 is provided 80 with a crank arm 15 carrying a roll 16 which rests against the periphery of a cam 17, said roll being held in contact with the cam by means of a spring 18, one end of which is secured to an arm 19 extending from the 85 rock shaft, and the other end of which is secured to the housing 7. 90

During the rotation of the housing 7 the rock shaft is carried about the cam 17 and the latter acts through the crank arm 15 to 100 vibrate said rock shaft and thus give the yarn-laying arm 12 its traversing movement. In apparatus of this type it is customary to so control the operation of the yarn-laying arm that each loop will be laid either immediately in advance of or immediately behind the previous loop, thus causing the loops to be laid in transverse layers. In the present construction this end is secured by a differential mechanism which gradually 105 shifts the position of the cam 17. Said cam 17 is made fast to a gear 20 which meshes 110

with an intermediate pinion 21 that is journaled on a stud 22 carried by the housing 7. This intermediate gear 21 also meshes with a stationary gear 23, said gear being held stationary by being fast on a sleeve 24 which in turn is made fast to the bearing 6.

The gear 20 has either one more or one less tooth than the gear 23 and since both gears are meshing with the pinion 21 and the latter is being rotated about the stationary gear 23 by the rotation of the housing 7, it will result that at each rotation of said housing 7, the gear 20 will be either advanced or retarded one tooth. The action 15 of the cam 17 will thus be either advanced or retarded slightly at each rotation with the result that the loops will be laid side by side as usual in devices of this character.

The apparatus herein shown is of that 20 type which has a compensating arm co-operating with the yarn-laying arm 12 for maintaining an even tension on the yarn during the vibration of the yarn-laying arm. This compensating arm is indicated 25 at 25 and it is carried by a vertical rock shaft 26 similar to the rock shaft 11, said rock shaft being journaled in a bearing 27 carried by the housing 7. The rock shaft 26 has at its upper end a crank arm 28 provided with a roll 29 which rests against the periphery of a compensating cam 30 which is rigid with the traversing cam 17. This compensating cam is designed to give the proper vibrating movement to the compensating arm 25 so that the latter will take up slack in the yarn when the yarn-laying arm 35 is moving toward the axis of rotation and give up yarn when the yarn-laying arm is moving in the opposite direction.

40 It will be noted that the mechanism for operating the yarn-traversing arm and compensating arm is very simple and comprises merely the two cams with the simple differential gearing. It is also entirely enclosed 45 within the housing 7 so that there are no exposed moving parts to be caught by the yarn.

40 My present invention also includes a novel 50 yarn-feeding device for positively feeding yarn to the winding head at a predetermined rate of speed. This feeding device is in the form of a friction feed wheel 31 which is fast on the shaft 5 at its upper end and which frictionally engages an idler or 55 presser wheel 32 that is journaled on a stud 33 carried by an arm 34 extending from the frame. The yarn 14 passes between the presser roll 32 and feed roll 31 and then passes down through the hollow shaft 5 to the compensating arm 25 and yarn-laying arm 12. I have illustrated the yarn guides 60 65 which serve to hold the yarn as it is fed by the feed roll 31. Since this feed roll is fast on the shaft 5 it will positively draw yarn from the source of supply at a speed

corresponding to that at which the yarn is wound and thus the compensating arm and yarn-laying arms are relieved entirely from any strain due to drawing yarn from the source of supply. The yarn will, therefore, 70 be laid under a constant tension at all times, thus producing a uniformly compact yarn mass 3. The yarn container 1 is shown as secured to a cap or head 41 which is carried by the member 6, and said yarn container 75 is so supported that when it is filled it can be disconnected from the housing 41 and lowered so as to withdraw it from the winding head, as shown in Fig. 6. When the yarn container has thus been filled and is 80 lowered to withdraw it from the winding head it is necessary to cut the yarn leading from the yarn mass to the winding plate before the container can be entirely removed 85 from the machine. When an empty yarn container is replaced in the machine it is necessary that the end of the yarn should be threaded through the slot 10 and held beneath the winding plate so that when the 90 machine is started said end will be retained on the yarn support thereby to ensure the proper winding action. I have provided herein an improved knife for thus severing the thread which is so constructed that the 95 severing of the thread can be done without de-threading the winding plate. One of the 100 bearings 27 has secured thereto a knife member 42 provided with a cutting edge 43, and the winding plate 8 has a notch 67 in its periphery. When the yarn container has 105 been lowered and withdrawn from the winding head, as shown in Fig. 6, the portion 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780

In Figs. 1, 2 and 3 I have shown the yarn-laying arm and compensating arm as mounted on separate rock shafts. In Figs. 6 and 7 I have shown a construction where these 120 two arms are carried by the same rock shaft which is indicated at 44. Where this construction is employed only one cam will be necessary instead of the two cams 17 and 30. The one-cam construction shown in Figs. 6 125 and 7 does not, however, give as perfect compensation as the two-cam construction.

I claim:

1. In a winding apparatus, the combination with a yarn receiver, of a rotatable 130

shaft, and a winding head mounted thereon, said winding head including a rock shaft situated non-axially of the winding head and extending parallel to the axis of rotation, a yarn-laying arm extending from said rock shaft, and a cam member about which the rock shaft is rotated by the head and which oscillates said shaft as the head rotates.

10 2. In a winding apparatus, the combination with a yarn receiver, of a rotatable shaft, and a winding head mounted thereon, said winding head including a rock shaft situated non-axially of the winding head and extending parallel to the axis of rotation, a yarn-laying arm extending from said rock shaft, a cam member about which the rock shaft is rotated by the head and which oscillates said shaft as the head rotates, and 15 compensating means acting on the yarn before it is delivered to said yarn-laying arm.

3. In a winding apparatus, the combination with a yarn receiver, of a rotatable shaft, and a winding head mounted thereon, said 20 winding head including a rock shaft situated non-axially of the winding head and extending parallel to the axis of rotation, a yarn-laying arm extending from said rock shaft, a cam member about which the rock shaft is rotated by the head and which oscillates said shaft as the head rotates, and a 25 vibrating compensating arm acting on the yarn before it is delivered to the yarn-laying arm.

35 4. In a winding apparatus, the combination with a yarn receiver, of a rotatable shaft, a winding head carried thereby and comprising a winding plate resting on the yarn and provided with a yarn-laying slot, two 40 rock shafts extending parallel to the axis of rotation of the shaft, a yarn-laying arm extending from one rock shaft, a compensating arm extending from the other rock shaft, and cam members about which said 45 shafts are carried during the rotation of the winding head and which cause said shafts to oscillate as the winding head rotates.

5. In a winding apparatus, the combination with a yarn receiver, of a rotatable shaft, 50 and a winding head mounted thereon, said winding head including a rock shaft situated non-axially of the winding head and extending parallel to the axis of rotation, a yarn-laying arm extending from said rock shaft, a cam member about which the rock shaft is rotated by the head and which oscillates said shaft as the head rotates, and means to give the cam a relatively slow rotation about the axis of rotation of the 55 shaft.

6. In a winding apparatus, the combination with a yarn receiver, of a rotatable shaft, and a winding head mounted thereon, said winding head including a rock shaft situated 60 non-axially of the winding head and

extending parallel to the axis of rotation, a 65 yarn-laying arm extending from said rock shaft, a cam member about which the rock shaft is rotated by the head and which oscillates said shaft as the head rotates, and 70 means actuated by the rotation of the shaft to give the cam a relatively slow rotative movement about said axis.

7. In a winding apparatus, the combination with a yarn receiver, of a rotatable shaft, 75 a winding head mounted thereon, said winding head including a rock shaft situated non-axially of the winding head and extending parallel to the axis of rotation, a yarn-laying arm extending from said rock 80 shaft, a cam member about which the rock shaft is rotated by the head and which oscillates said shaft as the head rotates, a gear rigid with said cam member, a second stationary gear, said gears having a different 85 number of teeth and both being situated in axial alinement with said shaft, and an intermediate gear meshing with both of the first-mentioned gears.

8. In a winding apparatus, the combination with a yarn receiver, of a rotatable shaft, 90 a supporting member or head fast thereto, two rock shafts journaled in said supporting member and extending parallel to the rotatable shaft, a winding plate suspended from 95 said supporting member, a yarn-laying arm extending from one rock shaft, a compensating arm extending from the other rock shaft, each rock shaft having a crank arm, two cam members axially alined with the 100 rotatable shaft and acting against said crank arms, and springs for maintaining said crank arms in engagement with said cams.

9. In a winding apparatus, the combination with a yarn receiver, of a rotatable shaft, 105 a supporting member or head fast thereto, two rock shafts journaled in said supporting member and extending parallel to the rotatable shaft, a winding plate suspended from 110 said supporting member, a yarn-laying arm extending from one rock shaft, a compensating arm extending from the other rock shaft, each rock shaft having a crank arm, two cam members axially alined with the 115 rotatable shaft and acting against said crank arms, springs for maintaining said crank arms in engagement with said cams, and means for rotating said cams slowly.

10. In a winding apparatus, the combination with a yarn receiver, of a rotatable 120 shaft, a supporting member or head fast thereto, two rock shafts journaled in said supporting member and extending parallel to the rotatable shaft, a winding plate suspended from 125 said supporting member, a yarn-laying arm extending from one rock shaft, a compensating arm extending from the other rock shaft, each rock shaft having a crank arm, two cam members axially alined with the 130 rotatable shaft and acting

- against said crank arms, springs for maintaining said crank arms in engagement with said cams, a gear rigid with said cams, a second stationary gear, a pinion carried by 5 said supporting member and meshing with both gears, said gears having a different number of teeth whereby the cams are gradually advanced by the rotary motion of the supporting member.
- 10 11. In a winding apparatus, the combination with a yarn receiver, of a winding head for laying the yarn in said yarn receiver in layers extending transversely to the axis of rotation, a hollow shaft on which 15 said winding head is supported and through which the yarn is delivered to the winding head, means for rotating said shaft, and a pair of feed rolls for delivering yarn to the hollow shaft, said feed rolls being situated 20 at the end of the shaft and one of them being rigid with the shaft.
12. In a winding apparatus, the combination with a yarn receiver, of a winding head for laying the yarn in said yarn receiver in layers extending transversely to the axis of rotation, a hollow shaft on which 25 said winding head is supported and through which the yarn is delivered to said head, means to rotate said shaft, a feed roll carried by said shaft at its upper end, a presser roll with which the feed roll has frictional contact, and means for guiding the yarn as it is led to the feed roll and from the feed roll to the end of the hollow 30 shaft.
- 35 13. In a winding apparatus, the combination with a yarn receiver, of a winding head comprising a supporting member, a winding plate connected to said member and provided with a yarn-laying slot, means for traversing the yarn in said slot, and a knife member carried by the winding head and situated above the winding plate.
- 40 14. In a winding apparatus, the combination with a rotatable yarn receiver adapted to contain a yarn mass, of a winding head resting on the yarn mass in the yarn receiver and operating to build up said mass in layers extending transversely to the 45 axis of rotation, a hollow shaft on which said winding head is supported, and means carried by said shaft for feeding yarn uniformly to the winding head.
- 50 15. In a winding apparatus, the combination with a yarn receiver, of a rotary winding head for laying the yarn in said 55 yarn receiver in layers extending transversely of the axis of rotation, a hollow shaft on which said winding head is sup-
- ported and through which the yarn is delivered to the winding head, means for rotating said shaft, a pair of feed rolls for delivering the yarn to the entering end of said shaft, one of said feed rolls being fixed on the shaft and the other supported independently thereof. 60
- 65 16. In an apparatus of the class described, the combination with a yarn receiver, of a winding head, means to give the winding head and yarn receiver a relative rotary movement, said winding head including a rock shaft situated non-axially thereof and extending parallel to the axis of the relative rotary movement, a yarn-laying arm extending from said rock shaft, 70 and means to oscillate said arm in a plane extending at right angles to said axis.
- 75 17. In an apparatus of the class described, the combination with a yarn receiver, of a winding head, means to give the 80 yarn receiver and winding head a relative rotary movement, said winding head including two rock shafts situated non-axially of the winding head but extending parallel to the axial line of the relative rotary 85 movement, a yarn-laying arm carried by one of the shafts, a compensating arm carried by the other shaft, and means for oscillating each arm in a plane perpendicular to said axis. 90
- 95 18. In an apparatus of the class described, the combination with a yarn receiver, of a winding head, means to give the winding head and yarn receiver a relative rotary movement, said winding head including a rock shaft situated non-axially thereof and extending parallel to the axis of the relative rotary movement, a yarn-laying arm extending from said rock shaft, 100 and a cam situated axially of the winding head for oscillating said rock shaft.
- 105 19. In an apparatus of the class described, the combination with a yarn receiver, of a winding head, means to give the winding head and yarn receiver a relative rotary movement, said winding head having two rock shafts both situated non-axially of the winding head but extending parallel to the axial line of the relative movement, a yarn-laying arm carried by one rock 110 shaft, a compensating arm carried by the other rock shaft, and a cam device situated coaxially with said winding head and operating to oscillate both rock shafts. 115
- In testimony whereof, I have signed my name to this specification.

CHARLES W. HUBBARD.
